UNITED STATES PATENT OFFICE.

HERMAN M. MOENCK, OF DETROIT, MICHIGAN, ASSIGNOR OF ONE-HALF TO GEORGE E. STREIT, OF DETROIT, MICHIGAN.

BUTTER-DISH.

1,041,659.

Specification of Letters Patent.

Patented Oct. 15, 1912.

Application filed January 29, 1912. Serial No. 672,416.

To all whom it may concern:

Be it known that I, HERMAN M. MOENCK, a citizen of the United States, residing at Detroit, county of Wayne, State of Michigan, have invented a certain new and useful Improvement in Butter-Dishes, and declare the following to be a full, clear, and exact description of the same, such as will enable others skilled in the art to which it pertains to make and use the same, reference being had to the accompanying drawings, which form a part of this specification.

This invention relates to butter dishes and has for its object a paper butter dish that can be shipped in flat form and put together, when desired to be used, without the use of either staples, paste, glue, or other fastening means.

It has additional advantages in being cheaper to manufacture and nests to better advantage than butter dishes requiring staples and without flexibility.

In the drawings:—Figure 1, is an elevation of the butter dish showing one end locked into position, while the other end is open. Fig. 2, is a view of the blank from which the dish is formed. Fig. 3, is a view of one of the corners showing the clamping piece in position.

The blank is cut in the form shown in Fig. 2, which in its general outline somewhat resembles an elliptical shape with projecting clamping pieces, one at each corner. The center of the blank A, is scored off into a rectangle B. From each corner of this rectangle, a pair of scored lines 2 and 3 diverge to the edge of the blank, the line 3 meeting the edge of the blank at one side of the clamping piece 1, the line 3 meeting the edge of the blank somewhat distant from the side of the clamping piece 1. The larger the angle between the scorings 2 and 3, the more upright will the sides C—C and the ends D—D stand. I prefer to make the angle between 2 and 3, about thirty degrees. This makes the butter dish of a convenient shape and affords a rounded connection between the end pieces D and the sides C, doing away with any corners.

When the gusset portions E are folded in, 50 the butter dish assumes the appearance shown at the right in Fig. 1. The clamping piece 1 is then folded in between the end D and the gusset E. This firmly holds the sides C in half upright position with the ends D and affords a rounding connection that does away with any corners. It is only with a rounded corner, such as the one shown, that the clamping piece will successfully interlock without the use of other fastening means. 60

If it is desired to ship the butter dishes in knock-down or flat condition, nothing more is necessary for the user to do, than to fold the gussets at the ends in and fold the clamping piece 1 over and between the gussets and the ends. Inasmuch, as dishes of this character are rarely ever used except once, the lock is sufficiently strong and the clamping piece is sufficiently rigid, until 70 it has been folded over several times, to firmly hold the ends and the sides together in upright relation.

If the dish is formed into shape by the manufacturer who stamps out the blank, it 75 may be very conveniently shipped by reason of the facility with which it nests, there being no staples to prevent proper nesting and there is sufficient flexibility in the connections between the sides and the ends to 80 allow the dishes to nest almost perfectly.

Should it be desired to make the dish somewhat stronger, a dot of paste may be used in connection with the folded in clamping piece, so as to stick the clamping piece 85 to the sides and ends, or to the ends.

What I claim is:—

A butter dish, comprising a blank scored to form the bottom of the dish, two side portions, two end portions and four triangular gusset portions connecting the end portions and the side portions and shaped to give the ends and the sides somewhat of an inclination from the vertical to provide the "flare" of the dish, and a clamping 90 piece attached to one of the members—as the end of the side member—and foldable, when the end of the side is bent in to pass 95

inside of the gusset, between the gusset portion and the adjacent portion—as the end portion, when the clamping piece is located on the side portion,—to lock the side and end, without any other fastening means, into angular position with reference to the bottom, substantially as described.

In testimony whereof, I, sign this specification in the presence of two witnesses.

HERMAN M. MOENCK.
